United States Patent Office

Des. 202,598
Patented Oct. 19, 1965

202,598

GROUP SOLARIUM

Mike Tecton, 5101 45th St. NW., Washington, D.C.

Filed Nov. 25, 1964, Ser. No. 82,790

Term of patent 14 years

(Cl. D83—1)

FIG. 1

FIG. 2

FIG. 3

FIG. 4

FIGURE 1 is a front perspective view of a group solarium embodying my new design;

FIGURE 2 is a top plan view thereof;

FIGURE 3 is a rear elevational view thereof;

FIGURE 4 is a side elevational view thereof.

I claim:

The ornamental design for a group solarium, substantially as shown.
